DESIGN FOR A FACE PLATE FOR A SIGNAL CASING

Medis C. Brady, Detroit, Mich.

Application April 12, 1938, Serial No. 76,456

Term of patent 7 years

To all whom it may concern:

Be it known that I, Medis C. Brady, a citizen of the United States of America, residing at Detroit, in the county of Wayne and State of Michigan, have invented a certain new, original, and ornamental Design for a Face Plate for a Signal Casing, of which the following is a specification, reference being had therein to the accompanying drawing, forming a part thereof, wherein—

Figure 1 is a front elevational view of a face plate for a signal casing showing my new design;

Figure 2 is an end elevational view of the face plate shown in Figure 1.

The design is characterized by an opaque face plate, as shown, having a double-ended arrow of contrasting color thereon, each of the arrowheads being provided with a lens mounted thereon substantially at the center thereof.

I claim:

The ornamental design for a face plate for a signal casing, substantially as shown and described.

MEDIS C. BRADY.
